ATTORNEY

UNITED STATES PATENT OFFICE

2,098,579

ENCLOSED SWITCH

Charles E. Hanny, Plainville, Conn., assignor to
 The Trumbull Electric Manufacturing Company,
 Plainville, Conn., a corporation of Connecticut

Application November 19, 1935, Serial No. 50,496

6 Claims. (Cl. 200—171)

This invention relates to enclosed switches, especially of the multi-pole type mounted within a box and operated by a handle outside the box. One object is to provide a device of this type in which the switch and its mounting may be easily and quickly inserted or removed from the box.

Another object is to provide a quick make and break type switch of this class in which the opening and closing movements of the switch are limited by abutments.

Another object is to provide such a switch which may be removable from the box in either open or closed position of the switch.

A further object is to provide an enclosed switch in which the movable switch members are actuated by a crank extending across the enclosing box and the movable switch members are connected to the crank by means of an insulating cross bar or bushing which is detachably secured to and around the crank.

Still another object is to provide means for spacing and for preventing relative movement between the cross bar and the crank in a direction longitudinal of the crank.

In multi-pole enclosed switches it has been customary to actuate the same through a link connected at one end to a crank extending across the enclosing box and at the other end connected to an insulating cross bar bridging the movable switch members.

Such a construction required more joints and more connections than were necessary and desirable. Also enclosed type switches of this sort are frequently mounted in boxes provided with automatic locking mechanisms which enable the cover of the box to be opened only when the switch is open. Sometimes this automatic interlock between the cover and the switch is difficult for one unfamiliar with the construction to understand and operate to close the switch with the box open.

According to this invention the switch construction is simplified by a reduction in the number of joints or connections and the switch so made that the entire switch and its base may be removed from the enclosing box.

Referring to the drawings:

Fig. 1 shows a top plan view of one embodiment of this invention with the cover of the box partly broken away.

Fig. 2 is a section on the line 2—2 of Fig. 1.

Fig. 3 is a section on the line 3—3 of Fig. 2.

Fig. 4 is a detail of the hook member connecting the movable switch part with the crank.

Fig. 5 is a similar view of a combined one-piece blade and hook.

Fig. 6 is an exploded perspective showing a crank shaft and a cross bar or bushing and the related blades and hooks.

Fig. 7 is a side view showing the same kind of cross bar or insulating bushing used with a double throw switch.

A customary type metal box 10 provided with perforations 9 in the base for securing the same to a wall, has the usual cover 11 secured to the box by hinges 12. Within the box an insulating base 13 for a switch is secured to the box by means of countersunk screws 14 which are in threaded engagement with stamped-in portions 15 of the bottom of the box, such portions being internally threaded to engage the screws.

Mounted on the insulating base are stationary switch members 16 of some usual construction adapted to receive the movable knife type switch members 17 pivoted at 18 so that the switch may be opened when the members 17 are swung upwardly out of contact with the stationary switch member 16. As is customary in constructions of this type the insulating base 13 may be provided with removable cartridge fuses 19 mounted in 25 the clips indicated.

For actuating the switch a handle 20 outside of the box is pivotally mounted and adapted to rotate the crank 21 and crank shaft which extends transversely across the box on the inside.

The handle is not necessarily directly connected to the crank shaft but may be connected therewith through a spring actuated toggle or other mechanism capable of giving the crank a rapid or snap movement for opening or closing the switch. Yieldable abutments 22 mounted on the inside of the box are engaged by the crank to limit the opening movement of the switch. The spring 23 is part of the toggle or quick make and break mechanism for actuating the crank.

Secured to the movable switch members 17 by rivets or other well known means are the hook shaped links 25. These links are secured to one side of the movable switch members 17 and secured contiguous the underside of the switch members 17 are insulating blocks 24 which are also fastened to the hook shaped members 25, as shown in Figs. 2 and 4. These blocks are preferably of some phenolic condensation product, or the like, but they may be slightly yieldable since their function is to act as stops to limit closing movement of the movable switch members 17, the members 24 engaging the insulating base 13. The hook shaped end of the members 25 engage grooves 26 in the cross bar or bushing 55

27 of insulating material. This cross bar engages the crank 21 loosely enough to permit rotation of the crank within the grooves in the cross bar, yet snugly enough to be free of any substantial lost motion.

To remove the switch and its insulating base from the box 10, the screws 14 are taken out after the connecting leads have been removed from each end of the base 13. Then by sliding 10 the cross bar, hook members, switch and insulating base until the crank 21 is out of the grooves of the cross bar or bushing 21, the switch and its insulating base may be withdrawn from the box. Boxes of this type frequently have an interlock mechanism which prevents the cover being opened when the switch is closed and allows the cover to be opened only when the switch is open. This mechanism also frequently prevents the switch being closed when the cover 11 of the 20 box is open.

To one unfamiliar with the operation of this interlocking mechanism it may be difficult to close the switch with the cover of the box open and for this reason the present invention has 25 been so designed that the switch and its mounting may be removed from the box irrespective of whether the switch be in the open or closed position. The grooves 26 in which the hook members 25 engage serve to hold the insulating 30 cross bar 27 against movement longitudinally of the crank and crank shaft and hold it in place without the addition of any rivets and the like.

A noteworthy feature of this invention is the simplification in construction, which enables the 35 insulating cross bar 27 to function as the connecting spacing and insulating bridge between the poles or blades of the switch, yet this bridging portion is possessed of the new function of serving as an insulating bushing around the 40 metallic actuating crank.

In the form shown in Figs. 5 and 6 the switch blade 17' has the connecting hook 25' integral with it.

In Fig. 7 I have shown a double throw switch 45 with stationary contacts 30 and 31 and the double bladed hinged switch member 32 adapted to be thrown from one closed position to another or moved to an intermediate open circuit position. The crank 33 is actuated in any suitable 50 manner. The cross bar 34 partially embraces the crank 33 and is grooved at 35 to be slipped in between the oppositely arranged blades of one or more pairs of movable switch members.

I claim:

55 1. As an article of manufacture, a connector for an electric switch formed of insulating material and having a longitudinal channel open at one side to detachably receive the crank shaft of a switch and having grooves in its outer wall spaced to interlock with the hooks of spaced switch blades.

2. An enclosed switch including a box having a cover, an insulating base removably fastened in the box, a multi-pole switch mounted on 60 said base and having stationary and movable switch members, a crank shaft with a crank portion extending across the box, an actuating handle outside the box for rotating the crank, an

insulating cross bar of U-shaped cross section on said crank, and links connecting said movable switch members and insulating cross bar, said links having hooks detachably engaging the cross bar and shaped to permit removal of said base 5 and switch from the box by sliding engagement or disengagement of the links from the said cross bar.

3. An enclosed switch including a box having a cover, an insulating base removably mounted 10 in the box, a multi-pole switch mounted on said base and having stationary and movable switch members, a crank shaft with a crank portion extending across the box, an actuating handle outside the box for rotating the crank, an insulating cross bar of U-shaped cross section on said crank, and links connecting said movable switch members and insulating cross bar, said links having hooks detachably connected with said cross bar to permit removal of said base and 20 switch from the box by sliding engagement and disengagement of the link from the cross bar, said links being received within exterior grooves on said insulating cross bar to preclude relative longitudinal movement between said cross bar 25 and crank.

4. An enclosed switch including a metal box having a cover, an insulating base, a stationary switch member on said base, a movable switch member pivotally mounted on the base, a crank 30 shaft having a crank portion extending across the box for opening and closing said switch, an actuating handle on the outside of the box for moving said crank, a hook fastened to the movable switch member and engaging said crank, 35 said hook being shaped to allow the switch member and its base to be attached or detached from the crank and from the box without removal of the crank, a U-shaped insulating cross bar around the crank and shaped for removal of said 40 switch and hook member, and means of engagement between the hook member and insulating cross bar limiting relative movement between the two longitudinally of the crank shaft.

5. An enclosed switch including a base having 45 a cover, an insulating base for the switch removably fastened in the box, a multi-pole switch mounted on said base and having stationary and movable switch members, a crank shaft having a crank portion extending across the box, an 50 actuating handle outside the box for rotating said crank, a U-shaped insulating cross bar loosely secured to the crank, a link connecting said cross bar and movable switch members for actuating the movable switch members by said 55 crank.

6. A multi-pole switch having movable and stationary switch members, an actuating crank for the movable switch members, an insulating cross bar connecting the movable switch members for actuating them in unison, said cross bar having a longitudinal groove open at one side to receive said crank, the connection between said insulating cross bar and the movable switch members including hook shaped portions detachably engaging with said cross bar.

CHARLES E. HANNY.
